(57) **CLAIM**

The ornamental design for a tree stand cover, as shown.

DESCRIPTION

FIG. 1 is a top perspective view of the tree stand cover in an assembled configuration;

FIG. 2 is a bottom perspective view of the tree stand cover in the assembled configuration;

FIG. 3 is a top view of the tree stand cover in the assembled configuration;

FIG. 4 is a bottom view of the tree stand cover in the assembled configuration;

FIG. 5 is a left side view of the tree stand cover in the assembled configuration, the left view being identical thereto;

FIG. 6 is a front view of the tree stand cover in the assembled configuration, the rear view being identical thereto;

FIG. 7 is an environmental view of the tree stand cover in the assembled configuration;

FIG. 8 is an inside perspective view of the tree stand cover in an open position;

FIG. 9 is an outside perspective view of the tree stand cover in the open position;

FIG. 10 is an inside elevation view of the tree stand cover in the open position; and,

FIG. 11 is an outside elevation view of the tree stand cover in the open position.

The broken line showing the tree structure is for the purpose of illustrating portions of the environmental structure and forms no part of the claimed design.

1 Claim, 6 Drawing Sheets
